OPTICAL ACCESSORY MOUNTING PLATE

Ronald S. Schwartz, Los Angeles, Calif., assignor to
Northrop Corporation, Beverly Hills, Calif., a corpora-
tion of California

Filed Oct. 15, 1963, Ser. No. 76,979

Term of patent 14 years

(Cl. D57—1)

FIGURE 1 is a side elevation of an optical accessory mounting plate showing my new design; the broken line showing is for illustrative purposes only.

FIGURE 2 is a rear elevational view as seen from the right of FIGURE 1.

FIGURE 3 is a front elevation view as seen from the left of FIGURE 1.

FIGURE 4 is a side elevational view as seen from the left of FIGURE 3.

FIGURE 5 is a plan view as seen from the top of FIG-
URE 4; and

FIGURE 6 is a plan view as seen from the bottom of FIGURE 4.

I claim:

The ornamental design for an optical accessory mount-
ing plate, substantially as shown and described.
